(57) **CLAIM**

The ornamental design for a window component extrusion, as shown and described.

DESCRIPTION

FIG. 1 is a top left perspective view of a window component extrusion showing my new design, which is broken in the center indicating indefinite length.

FIG. 2 is a bottom right perspective view thereof.

FIG. 3 is a top left perspective view of a second embodiment of a window component extrusion showing my new design, which is broken in the center indicating indefinite length; and, FIG. 4 is a bottom right perspective view thereof.
